US00D631914S

(12) **United States Design Patent**
Li

(10) **Patent No.:** **US D631,914 S**
(45) **Date of Patent:** **** Feb. 1, 2011**

(54) **PEN**

(75) Inventor: **Bin Li**, Ningbo (CN)

(73) Assignee: **Beifa Group Co., Ltd.**, Ningbo (CN)

(**) Term: **14 Years**

(21) Appl. No.: **29/357,152**

(22) Filed: **Mar. 8, 2010**

(30) **Foreign Application Priority Data**

Sep. 11, 2009 (CN) 2009 3 0208059

(51) **LOC (9) Cl.** **19-06**

(52) **U.S. Cl.** **D19/48**

(58) **Field of Classification Search** ..... D14/411, D14/431; D19/35, 36, 41, 42, 43, 44, 45, D19/46, 47, 48, 49, 50, 51, 54, 55, 56; 24/11 F, 24/11 P, 11 R; 401/6, 52, 99, 100, 104, 105, 401/106, 107, 108, 109, 192, 195, 243, 244, 401/245, 246, 247

See application file for complete search history.

(57) **CLAIM**

The ornamental design for a pen, as shown and described.

DESCRIPTION

FIG. 1 is an upper rear right perspective view of a pen showing my new design;

FIG. 2 is a right side elevation view thereof, with the left side elevation view being a mirror image of the right side elevation view;

FIG. 3 is a front elevation view thereof;

FIG. 4 is a rear elevation view thereof;

FIG. 5 is an enlarged top plan view thereof; and,

FIG. 6 is an enlarged bottom plan view thereof.

The broken lines showing a portion of the top of the pen in FIGS. 1 and 5 are included for the purpose of illustrating environment and form no part of the claimed design.

1 Claim, 3 Drawing Sheets
